(57) **CLAIM**

The ornamental design for an electric car charger, as shown and described.

DESCRIPTION

FIG. 1 is a front view of an electric car charger, showing my design;

FIG. 2 is a rear view thereof;

FIG. 3 is a front perspective view thereof;

FIG. 4 is a right side view thereof;

FIG. 5 is a left side view thereof;

FIG. 6 is a top plan view thereof; and,

FIG. 7 is a bottom plan view thereof.

The broken line showing in FIG. 2 represents portions of the ELECTRIC CAR CHARGER and forms no part of the claimed design.
